CLAIM

The ornamental design for a multiple compartment beverage container, as shown and described.

DESCRIPTION

FIG. 1 is a front perspective view of a multiple compartment beverage container showing our new design; FIG. 2 is a side elevation view thereof; FIG. 3 is a bottom plan view thereof; and FIG. 4 is a top plan view thereof.

The rear and side of the multiple compartment beverage container not shown are the same as FIGS. 1 and 2, respectively.
